GEORGE A. AMBLER, OF WINCHESTER, MASSACHUSETTS, ASSIGNOR TO UNITED SHOE MACHINERY COMPANY, OF PATERSON, NEW JERSEY, A CORPORATION OF NEW JERSEY.

ACTUATING MECHANISM FOR WORK-SUPPORTS.

1,029,839.

Specification of Letters Patent. Patented June 18, 1912.

Application filed June 30, 1905. Serial No. 267,842.

To all whom it may concern:

Be it known that I, GEORGE A. AMBLER, a citizen of the United States, residing at Winchester, in the county of Middlesex and 5 Commonwealth of Massachusetts, have invented certain Improvements in Actuating Mechanism for Work-Supports, of which the following description, in connection with the accompanying drawings, is a specification, like reference characters on the drawings indicating like parts in the several figures.

This invention is applicable to many classes of machines but is particularly 15 adapted for use in machines employed in the manufacture of boots and shoes for inserting slugs, protectors, fastenings and the like into work sustained upon a work support.

20 Specifically, the invention relates to the mechanism in such machines for actuating the work support.

In the type of machine to which this mechanism is preferably applied, the work, 25 at the time the slug or fastening is inserted, is clamped between the work support and a foot plate or similar abutment but is released while the work is being fed. As the thickness of the work varies, the work support 30 must occupy varying positions relatively to the fixed foot-plate at the time the work is clamped. Commonly, the work support is raised to clamp the work by a spring. In order, however, that the work support 35 shall be held firmly against the blow or force exerted by the mechanism for inserting the slug or fastening, it has been proposed either to provide additional mechanism for locking the work support or else 40 to make the spring which constantly tends to raise the work support very heavy or strong. The employment of such a heavy spring is objectionable for the reason that considerable effort must be exerted by the 45 operator in order to lower the work support when the work is to be removed or replaced. On the other hand, when the work support is raised by a light spring, it is desirable to give an additional upward movement to the 50 work support to clamp the work more firmly and to compress it during the time and just before the inserting mechanism is delivering its blow.

The present invention comprises broadly, 55 mechanism for raising and lowering a work

support, or a carrier for a work support, which mechanism includes connections having means for rendering said mechanism inoperative for actuating the work support or its carrier. Preferably, this actuating 60 mechanism acts positively but an additional means, such as a spring, is provided which constantly tends to move the work support or carrier in one direction and this additional means becomes operatively effective 65 when the above described connections to the work support or carrier, which may include one or more clutching devices, are rendered inoperative.

In the preferred embodiment of the invention hereinafter described in detail, a positively reciprocated actuating member is provided with two clutching devices for locking it firmly to a coöperating reciprocable member connected to the work support. 70 These clutching devices are located most conveniently on the actuating member and are adapted to be thrown automatically into and out of engagement with the adjacent face of the other coöperating member. Means are 75 provided for maintaining one clutching device normally inoperative and for causing the other device to tend constantly to move into engaging position, the engagement and release of these devices being controlled 80 automatically at the proper times by fixed stops which may be located upon the machine frame. With this construction, one of the clutching devices, when permitted to do so, will operatively connect the actuating 85 member to the work support or its carrier to release the work during the feed. Then this device will be thrown out of operation automatically and the work support or carrier will be held yieldingly in raised position 90 after which the other clutching device will be thrown into operation at the desired point in the cycle of operations, so that the work support or carrier will be positively raised a distance which may be adjusted, 100 thus compressing the work, and also causing the work support to sustain the work firmly against the blow of the mechanism for inserting the slug or fastening.

The present invention also comprises specific combinations of parts and certain details of construction which will be hereinafter described and claimed.

Referring to the accompanying drawings, Figure 1 is a view in side elevation of a part 110

of a machine for inserting protectors and slugs or fastenings in which is embodied the mechanism for actuating the work support forming the subject of the present invention; Fig. 2 is a similar view on a larger scale of a part of said mechanism including the clutching devices, a part of the actuator or slide E being shown in central section; and Fig. 3 is a perspective view of the same parts as are shown in Fig. 2 some of them being partially cut away.

The drawings show the invention applied to the machine for inserting protectors and slugs or fastenings which is the subject of Letters Patent of the United States No. 995,050, granted June 13, 1911 upon an application filed November 9, 1903, and bearing Serial Number 180,296. While the mechanism of the present invention is well adapted for use in a machine for inserting protectors and fastenings such as is fully described in said Letters Patent, yet it will be evident from the following description that this mechanism may be employed equally well in many other types of machines.

Referring to the drawings, A represents a column having a suitable foot A¹ and a hollow post A' upon which the work support is carried. The head A² of the column sustains the parts which coöperate to insert protectors and fastenings into the work in the manner fully described in said pending application. The present invention does not include these specific parts and therefore they will not be further described herein.

The work C⁸ is held between the foot plate A⁷ and any suitable work plate C⁷ or other support. As shown in the drawings the plate C⁷ rests upon a table B⁷ having a hollow shank D which fits over the holder B⁹ fixed to the spindle B. A spiral spring D³ is interposed between the upper end of holder B⁹ and a shoulder within the hollow shank D, the relative movement of the shank D upon the holder B⁹ being limited by a stud D² in the shank which enters a slot D' in one side of the holder.

The main shaft B⁶ in the head A² carries a cam B⁵ provided at one side with a cam groove B^{2x} in which runs a roll or stud B⁴ upon a lever B² pivoted at B³ and provided with a slot by which it is adjustably connected to a rod B' from which the spindle B is reciprocated through connections about to be described.

The structure so far detailed is or may be substantially the same as that designated by the same reference letters in the Letters Patent previously mentioned. This specific construction however, forms no part of the present invention which relates particularly to the connections between the source of power and a work support of any suitable

kind. For many classes of work, the horn, or other support for the work, is secured directly to the spindle or carrier B or, if desired, made integral therewith. The term "carrier" therefore as used in this description and in the claims is intended to designate a member to which the part directly engaging and supporting the work is connected, whether such connection be integral, positive or yielding.

As illustrated, the rod B' is pivoted at its lower end to an actuator, shown as a reciprocable slide E which may be automatically connected to and disconnected from a coöperating member or slide F. The slides E and F are confined by cap plates A⁸, A⁹ in suitable guideways formed by lugs projecting from the column A. A pawl E' pivoted in a recess in slide E is normally forced into engagement with ratchet teeth F' on slide F by means of a plunger or pin E² pressed forwardly within a hole in slide E by a spring E³ which bears against an adjustable screw E⁴ having a lock nut E⁵. As shown in Fig. 3, the pawl E' is extended laterally so that it is adapted to come into engagement with the inclined face of a fixed stop A¹⁰ forming part of the cap plate A⁹. As the actuator E descends, the extension of pawl E' comes into contact with stop A¹⁰ and the pawl is withdrawn from the ratchet teeth F', as shown in Fig. 2. The point at which this withdrawal takes place may be varied by adjusting the cap plate A⁹ laterally, it being slotted at A¹¹, A¹² for that purpose. This clutching device is adapted to connect the actuator E and member or slide F to depress carrier B so as to release the work clamped between the plate C⁷ or other work support and the foot plate A⁷, thus permitting the work to be fed as will be further explained.

A second clutching device is provided also for connecting actuator E and slide F to raise the carrier B and the work support C⁷ positively. Upon the same side of the actuator as the recess for the pawl E' is another recess which, with the adjacent side of the slide F, forms a tapering chamber or pocket E⁷ in which is located a roll E⁸. A pair of light springs E⁹, seated in sockets which extend downwardly from the chamber E⁷, bear against roll E⁸ and tend to force it into the narrow end of the chamber so that the slides E and F will be locked together upon the downward movement of slide or actuator E. This effect of the spring E⁹ is normally negated, however, by a spring pressed plunger E¹⁰ provided with a head which directly engages the roll E⁸. This plunger is received in a longitudinal central slot E¹¹ in the front face of actuator E the slot being narrowed at its upper end to form shoulders E¹² against which is seated a washer E¹³ loosely mount-

ed on plunger E¹⁰. A spring E¹⁴, surrounding the plunger between its head and the washer E¹³, is of such strength that, in opposition to the springs E⁹, it forces the plunger downwardly carrying the roll E⁸ into the wider end of chamber E⁷ where it is ineffective to lock the slides E and F together. For retracting the plunger to allow the roll clutch to become operative, the plunger E¹⁰ is secured to a cross piece E¹⁵ capable of a limited vertical movement in a transverse slot E¹⁶ in the face of actuator E. The ends of this cross piece extend beyond the sides of the actuator and are widened as indicated in Fig. 3. A pair of stop screws E¹⁷ in these extended ends of the cross piece are arranged to come into contact respectively with the cap-plate A⁸ and another fixed part of the frame, as shown in Fig. 3, just before the actuator reaches the lower limit of its movement whereby the plunger is retracted and the roll E⁸ is caused to lock the slide F to the actuator E. The point at which this locking takes places may be varied by the adjustment of the screws E¹⁷ which are retained in adjusted position by set screws E¹⁸.

The slide F is connected at its lower end to a rod F² which is pivoted also to a lever G loosely pivoted on a rock shaft G' mounted in the foot A⁰ of the column A. A rod G² secured to the spindle or carrier B is pivoted at its lower end to lever G. A light spring G³ surrounds the rod G² bearing at its lower end upon a plate or shoulder G⁴ in the foot A⁰ and at its upper end against an adjustable nut G⁵ threaded on the rod G². The spring G³ is of such a strength as to tend constantly to raise carrier B so as to clamp the work lightly between its support C⁷ and the foot plate A⁷.

In order that the operator may depress carrier B and the work support C⁷ for the purpose of inserting or removing work, a counter weighted treadle G⁶ is fixed to the rock shaft G' and an arm G⁷ also fixed to the shaft, is arranged to engage lever G near its rear end. This treadle, therefore, constitutes an independent means for releasing the work at any time during the cycle of operations except when the roll E⁸ is operative to lock the slides E and F together.

Assuming the actuator E to be somewhat above its lowermost position with both clutching devices in inoperative position, the carrier or the work support being maintained in engagement with the work by spring G³ and spring D², if the latter is employed, now as the actuator E rises, the pawl E' leaves the inclined face of the stop A¹⁰ and engages, according to the thickness of the work, one of the ratchet teeth F' whereby the final upward movement of the actuator causes a positive depression of the

carrier B thus relieving the pressure of the work against the foot plate. In the particular machine illustrated and fully described in the Letters Patent above referred to, it is desirable that the plate C⁷ be yieldingly elevated by spring D² so that while the machine is running the work C⁸ will always be held against the foot plate A⁷. It is obvious, however, that by an adjustment of the stop plate A¹⁰ or of the rod B' along the slot in lever B², the carrier B may be given a greater downward movement so that by the engagement of stud D² with the end of slot D' the work may be drawn away positively from the foot plate. Also, in the form of the invention, where the work support is fixed to, or integral with, the carrier B, the work is drawn away from the foot plate a predetermined distance when the work is to be fed. At the desired point in the downward movement of actuator E, pawl E' is thrown out of engagement with the ratchet teeth F' by contact with the stop A¹⁰ whereupon the work is forced against the foot plate A⁷ by the action of spring G³ upon carrier B, the lower end of shank D seating itself firmly upon the shoulder of holder B². Just before the actuator E reaches the lower limit of its stroke, the screws E¹⁷ come into contact with their co-operating fixed stops so that the plunger E¹⁰ is withdrawn from roll E⁸ allowing it to lock together slides E and F whereby the carrier B and the work support C⁷ are raised positively a short distance to clamp the work more firmly and to sustain it rigidly against the blow of the inserting mechanism. Soon after the actuator begins to rise again, the spring E¹⁴ moves the plunger downwardly relatively to the actuator and thus roll E⁸ is moved into inoperative position.

While for convenience and for clearness, the mechanism which embodies the present invention has been described as applied to a particular machine, it will be understood that the same mechanism may be applied without substantial changes to various other machines and especially to machines for nailing, pegging or slugging in which it is desirable alternately to clamp and to release the work. Furthermore, it is obvious that various changes in addition to those already suggested, may be made in details of construction, without departing from the substance and spirit of the invention as defined in the claims.

Therefore, what I claim as my invention and desire to secure by Letters Patent of the United States is:—

1. In a machine provided with a work abutment, a work support movable into and out of work clamping relation to said abutment, a spring tending normally to maintain said work support in operative relation to the work abutment, means for intermittently de-

pressing the work support against said spring to permit the work to be fed constructed to restore the work support to the control of the spring at a point between its 5 extreme depression and its operative position, means for locking the work support in operative position comprising a roll spring-pressed into locking position, and means for preventing said roll from acting until after 10 the work support controlling spring has been permitted to adjust the work support to the thickness of the work.

2. In a machine provided with a work abutment, a work support movable into and 15 out of work clamping relation to said abutment, a spring tending normally to maintain said work support in operative relation to the work abutment, intermittently operated means for positively depressing the work 20 support against said spring to permit the work to be fed constructed to restore the work support to the control of the spring at a point between its extreme depression and its operative position, means for bringing a 25 positive clamping pressure to bear upon the work and to lock the work support in its work clamping position comprising a roll arranged in a tapered pocket between said means and a part connected with the work 30 support, and means for preventing said roll from locking said parts together until after the spring has been permitted to adjust the work support to the thickness of the work.

3. In a machine of the class described, a 35 power shaft, a work support and mechanism for actuating it, comprising a movable member connected with the work support, a second member positively reciprocated from said shaft, constructed and arranged to 40 transmit movement to said first-named member, and clutching devices for connecting and disconnecting said members, comprising respectively a pawl and ratchet and a roll coacting with the walls of a tapering pocket 45 located between said members, said devices when operative acting to move the work support respectively in opposite directions, and stops for controlling the operation of said clutching devices.

50 4. In a machine of the class described, a carrier, a reciprocable member positively connected to the carrier, a coöperating member one side of which slides against one side of the first member, a plurality of clutching

devices carried upon the side of one of said 55 members and adapted to engage the adjacent side of the other member to lock said members together, means coöperating with each of said devices for throwing them automatically into and out of operation successively 60 and a spring acting to move the carrier so as to compensate for different thicknesses of work.

5. In a machine of the class described, a carrier, a spring acting normally to maintain 65 the carrier in raised position, a pivoted lever connected to the carrier, a reciprocating member connected to said lever, a coöperating member having one side only in sliding engagement with the reciprocating member, 70 a clutching device acting normally to lock said members together when the said coöperating member is moved in one direction, a second clutching device which may be actuated to lock said members together when 75 said coöperating member is moved in the opposite direction, and adjustable automatic means for first disconnecting one of said devices and then after said spring has raised the carrier, for rendering the other device 80 operative to lock said members together, whereby the carrier is raised positively a predetermined distance to clamp and firmly to sustain the work.

6. In a machine of the class described, a 85 carrier, a reciprocable member positively connected to the carrier, a coöperating member in sliding engagement with the first member, a clutch part at one side of the second member adapted normally to engage 90 the adjacent surface of the first member, another clutch part on the same side of said second member but normally maintained out of engagement with the first member, and fixed stops adapted during the movement 95 of the second member in one direction to throw the first clutch part out of operation and thereafter to throw the other clutch part into position to lock the said members together.

100 In testimony whereof I have signed my name to this specification in the presence of two subscribing witnesses.

GEORGE A. AMBLER.
